United States Patent Office

Des. 191,734
Patented Nov. 7, 1961

191,734

HAIR DRYER HOOD OR SIMILAR ARTICLE

Theodore G. Daher and Robert J. Reading, Stratford,
Conn., assignors to General Electric Company, a cor-
poration of New York

Filed Oct. 27, 1959, Ser. No. 58,082

Term of patent 14 years

(Cl. D86—10)

FIG. 1.

FIG. 2.

FIG. 3.

FIG. 1 is a rear perspective view of a hair dryer hood embodying our new design;

FIG. 2 is a front perspective view thereof; and

FIG. 3 is a side elevational view thereof.

We claim:

The ornamental design for a hair dryer hood or similar article, substantially as shown.
